UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPE-BAR REST.

1,266,859.

Specification of Letters Patent. Patented May 21, 1918.

Application filed November 7, 1914. Serial No. 870,774.

To all whom it may concern:

Be it known that I, ALVAH C. ROEBUCK, a citizen of the United States, residing at Woodstock, in the county of McHenry and State of Illinois, have invented certain new and useful Improvements in Type-Bar Rests, of which the following is a specification.

This invention relates to a typewriter and to that portion of a typewriter upon which the type bars are supported when they are at rest.

The principal object of this invention is to provide a type bar rest which is simple and inexpensive to manufacture and construct and in which there is the least possible rebound due to the impact of the type bars as they are returned from the printing position.

Another object is to provide a suitable cushion for the type bars by means of which the impact is reduced to as great an extent as possible so that there is no tendency to rebound and in order to prevent the collision and locking of the type bars at the type end.

Other objects will be hereinafter set forth.

In the accompanying drawing, Figure 1 is a perspective view of a portion of the top plate of a typewriting machine with a curved portion in which the cushioning material of the type bar rest is seated; Fig. 2 is a view in elevation showing the type bar rest in section. Fig. 3 is a sectional view taken on the line 3—3 of Fig. 2. Fig. 4 is a top view of the cushioning material. Fig. 5 is a side elevation of the cushioning material.

In a type bar rest, the principal object is to prevent rebound of the type bars, and another object is to provide a construction which is as nearly silent as possible in action. In some constructions, the cushioning material is attached to a strap of sheet metal which is supported on the frame of the machine, while others use various constructions and combinations to deaden the sound, to diminish the impact and to prevent the rebound.

In the present construction, the cushioning material is disposed directly upon an integral curved portion 6 of the top frame 7 which extends in front of the machine, preferably in the form of a crescent of which about half is shown in Fig. 1. This curved portion 6 is formed with a flange 8 behind

which is a groove 9 and an inclined portion 10 in which is a recess 11 with small grooves 12 in the bottom. Seated in the recess 11 which extends substantially the full length of the curved portion 6, is the cushioning material upon which the type bars directly rest. This cushioning material consists of a piece of felt 13 covered by a strip of what is known to the trade as light weight both sides ooze calf-skin, usually known to the public as suede, or chamois-skin, designated generally by the reference numeral 14, both of these leathers having the outer or hair side of the skin removed, so as to give it a rough surface and make it softer and less resilient. The small grooves 12 in the bottom of the recess 11 are for containing adhesive substance such as glue, for holding the felt in place. The felt is secured to the leather by stitching or by adhesive material, or by both, and the ends of the leather strip 14 extend beyond the felt and are secured to the frame 7 by fastening devices 15. It is found that chamois, suede, or an undressed leather of this kind, is particularly adapted for use in this connection for the reason that it is almost entirely without resilience, while a finished leather has a tendency to produce a rebound. By further cushioning this chamois or suede with felt, the rebound of the type bars is almost entirely prevented and the supporting frame being firm and unyielding, practically eliminates the noise. While a single strip of felt under the leather is considered preferable, it is obvious that several strips of felt or other fabric may be used.

Each of the fastening devices 15 preferably comprises a nut 16, a bolt with a round head 17 cut away on one side 18, and of a size to fit in a recess 19 in which the end of the leather strip 14 is seated, so that when the nut is tightened on the bolt, the end of the leather strip 14 is completely hidden, thus presenting a neat and finished appearance.

What I claim is:

1. In a typewriting machine, a single piece frame plate extending over the top of the machine from front to rear and formed at the front with an integral type bar rest curved downwardly at the center and with an upwardly opening groove in the curved portion, and a non-resilient pad secured in the groove.

2. A type bar rest curved downwardly at the center with an upwardly opening longitudinal recess in the curved portion and grooves in the bottom thereof for containing adhesive material, and an anti-rebound cushion disposed in the recess and held in place by adhesive material.
3. In a typewriting machine, a top frame plate formed at the front with a portion curved downwardly at the center and having an upwardly opening longitudinal recess with longitudinal grooves in the bottom for confining adhesive material, and a non-resilient pad secured in the groove.
4. In a front strike typewriting machine, a type bar rest consisting of a frame plate with an integral curved portion concavely curved from the horizontal in which is an upwardly opening longitudinal recess with a plurality of grooves in the bottom for containing adhesive material and an anti-rebound cushion disposed in the recess and held in place by adhesive material.
5. In a front strike typewriting machine, a type bar rest consisting of a frame plate formed with a concavely curved portion in which is a longitudinally extending upwardly opening recess with a plurality of grooves in the bottom, adhesive material disposed in the grooves for holding the cushioning material in place, and means at the ends of the recess for securing the cushioning material at the ends.
6. In a front strike typewriting machine, a type bar rest consisting of a top plate formed with a concavely curved portion at the top of the plate, non-resilient material secured to the top of the curved portion, an ooze leather strip secured to the non-resilient material and over-lapping it at the ends, and means for securing the over-lapping ends of the ooze leather to the curved portion of the frame.
7. In a front strike typewriting machine, a type bar rest consisting of a top frame plate with a curved portion formed integral therewith at the front in which is an upwardly opening concave longitudinally extending recess with a plurality of grooves in the bottom, a strip of felt disposed in the recess, adhesive material in the grooves for holding the felt in place, a strip of ooze leather in connection with the felt and over-lapping it at the ends, and fastening devices for securing the overlapping ends to the frame plate.
8. A type bar rest curved downwardly at the center with an upwardly opening longitudinally grooved recess, a non-resilient pad for the recess, adhesive material in the grooves for holding the pad in the recess, and additional holding means for the pad at the ends of the recess.
9. In a type bar rest, the combination with a frame element, having recesses at the sides, of an anti-rebound cushion supported thereby with the ends thereof disposed in the recesses, and a fastening device comprising a bolt with a broad flat head adapted to be inserted through the end of the cushion and through the frame, the head substantially filling the recess and covering the end of the cushion, and means to bind the bolt and cushion in place.
10. A type bar rest comprising a frame plate formed with a longitudinal grooved recess and with other recesses at the end of the grooved recess, of an anti-rebound cushion disposed in the grooved recess having its ends in the other recesses, means to hold the cushion in the grooved recess, and a bolt with a head adapted to fill the recess and to hide and bind the end of the cushion therein.
11. In a front strike typewriting machine, the combination with a top frame plate formed at the front with a portion curved from the horizontal in a vertical plane and less than a semi-circle in extent having an upwardly opening recess with longitudinally extending grooves therein, of a non-resilient pad consisting of a strip of felt and a longer strip of leather secured thereto, adhesive material disposed in the grooves in the bottom of said recess to fasten the felt of the pad, and fastening means consisting of flat headed bolts for securing the leather projecting ends to the plate at the ends of the curved portion.

In testimony whereof I have signed my name to this specification, in the presence of two subscribing witnesses, on this 4th day of November, A. D. 1914.

ALVAH C. ROEBUCK.
